SPRAY CAN ATOMIZING PUMP

Alister B. Macnaughton, P.O. Box 16111,
Phoenix, Ariz.

Filed Aug. 5, 1965, Ser. No. 86,462

Term of patent 14 years

(Cl. D62—2)

FIG. 1 is a perspective view of the spray can atomizing pump of this invention.

FIG. 2 is a left hand side elevation of the device shown in FIG. 1.

FIG. 3 is a front elevation of the device shown in FIG. 1.

FIG. 4 is a plan view of the device shown in FIG. 1. The broken lines are for illustrative purposes only.

I claim:

The ornamental design for a spray can atomizing pump, as shown and described.
